[57] ABSTRACT

Harmonic limiting is employed in an electronic musical instrument of the type wherein notes are produced by computing the amplitudes at successive sample points of a musical waveshape and converting these amplitudes to notes as the computations are carried out in real time. Each amplitude is computed by accumulating as many as W individually calculated waveshape discrete Fourier components. In accordance with the present invention, harmonic inhibit means are provided for limiting the Fourier components included in each amplitude computation only to those having frequencies below a certain value preferably within the normal human hearing range.

COMPUTOR ORGAN USING HARMONIC LIMITING

BACKGROUND OF THE INVENTION

Field of the Invention

The present invention relates to a system for reducing the computational rate requirements of an electronic musical instrument wherein tones are produced by computing the amplitudes at successive sample points of a complex waveshape and converting these amplitudes to musical sounds as the computations are carried out. The system limits the Fourier components calculated for each sample point to ones having a frequency below a selected value within the human hearing range.

Related Applications

The present invention is related to the inventor's co-pending U.S. patent applications Ser. No. 225,883, filed on Feb. 14, 1972 entitled COMPUTER ORGAN and No. 298,365, filed on Oct. 17, 1972 entitled COMPUTER ORGAN USING PARALLEL PROCESSING.

Description of the Prior Art

A unique method of digital waveshape generation in an electronic musical instrument is disclosed in the above mentioned U.S. patent application entitled COMPUTER ORGAN. Therein, waveshape synthesis is accomplished by computing the sample point amplitudes of a complex waveshape at regular time intervals, and converting these amplitudes to musical notes as the computations are performed in real time. A discrete Fourier algorithm is implemented to calculate the individual harmonic components at each sample point, using a stored set of harmonic coefficients which characterize the resultant waveshape. The calculations are carried out at a constant time rate regardless of the note fundamental frequency. One method of reducing the computational rate requirement in a computor organ of this type is set forth in the above mentioned U.S. patent application entitled COMPUTER ORGAN USING PARALLEL PROCESSING. In that system, different subsets of the Fourier components are computed in separate parallel processing channels. For example, in a computer organ wherein sixteen Fourier components are evaluated to obtain each sample point amplitude, the computational rate can be halved by concurrently calculating eight components in one processing channel and the other eight harmonics in a second, parallel channel.

An object of the present invention is to provide another approach for reducing the computational rate requirements of such a computor organ. The computational rate is determined in part by the highest frequency component generated by the system. Since the human hearing range is limited, there is no need to generate components above some upper value within that range. By limiting the calculated Fourier components to such range, a significant reduction in computation rate is achieved. Harmonic limiting can be used by itself, or in conjunction with the previously described parallel processing to obtain an even greater reduction in system clock rate.

SUMMARY OF THE INVENTION

In a computor organ of the type described, the musical waveshape is generated in real time. This advantageously (but not necessarily) is achieved by computing each sample point amplitude in a fixed time interval t_x . All of the individual Fourier components are calculated within that interval. For accurate waveshape synthesis, the sample rate must be greater than the Nyquist frequency f_N which is twice the frequency f_h of the highest Fourier component evaluated by the system. By way of example, the highest eight-foot pitch on a standard organ keyboard is C_7 which has a fundamental frequency $f_H = 2.093$ kHz. If 16 Fourier components are calculated to synthesize this tone, the highest frequency f_h evaluated by the organ corresponds to the sixteenth harmonic of C_7 . That is:

$$f_h = 16f_H = 16(2.093 \text{ kHz}) = 33.488 \text{ kHz} \quad (1)$$

Accordingly, the Nyquist frequency f_N is:

$$f_N \geq 2f_h = 66.976 \text{ kHz} \quad (2)$$

This sets the upper limit for the computation interval t_x as:

$$t_x \leq 1/f_N \quad (3)$$

However, all of the individual harmonic calculations must be carried out within this interval t_x . Thus if sixteen Fourier components are evaluated in a single channel, each calculation must be performed in a clock time $t_{cp} = t_x/16$. Accordingly, the system computational clock rate f_c for a monophonic instrument is given by:

$$f_c = 1/t_{cp} = 16/t_x \geq 16 f_N = 16(66.976 \text{ kHz}) = 1.072 \text{ MHz} \quad (4)$$

For a polyphonic organ in which K notes may be played at once, the harmonic components of all notes must be evaluated for each sample point within the time interval t_x . Thus for a polyphonic, single channel instrument, the system computational clock rate f'_c is given by:

$$f'_c = Kf_c \quad (5)$$

In a system where $K = 12$, permitting ten keys and two pedal notes to be played simultaneously, the computational clock rate f'_c is:

$$f'_c = 12 f_c \geq (12)(1.072 \text{ MHz}) = 12.859 \text{ MHz} \quad (6)$$

This relatively high computational clock rate may be reduced significantly using the harmonic limiting system of the present invention. The system takes advantage of the fact that for notes in the fifth and sixth octaves, many of the higher harmonics are above the hearing range of the average listener. For example (see

Table I below), the sixteenth harmonic of the note C₈ (the key of C in octave 6) is 16.744 kHz which is above the hearing range of the average adult. At C₇, the sixteenth harmonic is 33.488 kHz, far outside the normal hearing range. Accurate waveshape synthesis without significant loss of realism or fidelity can be achieved using only those harmonics having frequencies below some limit within the hearing range of the typical listener. By excluding harmonic components above this limit from the wave-shape amplitude computations, the Nyquist frequency is reduced, with concomitant reduction in the system computational clock rate.

As an illustration, the waveshape amplitudes may be computed using only those harmonics having a frequency below 12.9 kHz. As evident from Table I, all sixteen Fourier components will be included in the amplitude computations for each note up to and including G₅. For these notes, the sixteenth harmonic has a frequency below 12.9 kHz. For G₆ #5, only fifteen Fourier components will be included in the amplitude computation, since the sixteenth harmonic has a frequency above 12.9 kHz. Similarly, for other notes between G₆ #5 and C₇ the amplitude computations will be limited to the harmonics indicated in Table I. At C₇, only six components will be employed to synthesize the wave-shape, since the sixth harmonic has a frequency of 12.558 kHz and the seventh harmonic lies above 12.9 kHz.

The Nyquist criteria discussed above may be applied to this illustration to determine the system clock rate requirements. Since the highest frequency component (the 13th harmonic of B₅) evaluated by the system has a frequency $f_h = 12.841$ kHz, the computational clock rate f_c for a monophonic instrument is:

$$f_c \geq 16 f_h \geq (16)(12)(12.841 \text{ kHz}) = 410.9 \text{ kHz} \quad (7)$$

and the computational rate f_c' for a twelve note (K = 12) polyphonic system is:

$$f_c' \geq 12 f_c = 4.930 \text{ MHz} \quad (8)$$

Thus for a computer organ in which the harmonic components are limited to those below 12.9 kHz, the computational rate is reduced by a factor of about 2.66 as compared with a system wherein all sixteen harmonics are computed for every note up to C₇. Clearly this represents a very significant reduction in the system computational rate, and permits the computer organ more readily to be implemented using presently available microelectronic integrated circuits.

BRIEF DESCRIPTION OF THE DRAWINGS

A detailed description of the invention will be made with reference to the accompanying drawings, wherein like numerals designate corresponding parts in the several figures.

FIG. 1 is an electrical block diagram of a computer organ employing harmonic limiting.

FIG. 2 is an electrical block diagram of a first embodiment of the harmonic inhibit logic utilized in the computer organ of FIG. 1.

FIG. 3 shows typical musical waveshapes generated by a computer organ employing the harmonic inhibit logic of FIG. 2.

FIG. 4 is a timing diagram illustrating inhibition of the Fourier component calculations during generation of the musical waveshapes illustrated in FIG. 3.

FIG. 5 is an electrical block diagram of an alternative embodiment of the harmonic inhibit logic utilized by the computer organ of FIG. 1.

FIG. 6 shows typical musical waveshapes generated using the harmonic inhibit logic of FIG. 5.

FIG. 7 is a timing diagram illustrating harmonic limiting in a polyphonic computer organ.

FIG. 8 is an electrical block diagram showing implementation of harmonic limiting in a parallel processing computer organ.

DESCRIPTION OF THE PREFERRED EMBODIMENTS

The following detailed description is of the best presently contemplated modes of carrying out the invention. This description is not to be taken in a limiting sense, but is made merely for the purpose of illustrating the general principles of the invention since the scope of the invention best is defined by the appended claims.

Structural and operational characteristics attributed to forms of the invention first described shall also be attributed to forms later described, unless such characteristics are obviously inapplicable or unless specific exception is made.

The computer organ 10 of FIG. 1 operates to produce via a sound system 11 a musical note selected by the keyboard switches 12. This is accomplished by calculating the discrete Fourier components associated with amplitudes at successive sample points of a wave-shape characterizing the selected note. The components are algebraically summed in an accumulator 13 which, at the end of each computation time interval t_x contains the amplitude at the current sample point. This amplitude is provided via a gate 14, enabled by the t_x signal on a line 15, to a digital-to-analog converter 16 which supplies to the sound system 11 a voltage corresponding to the waveshape amplitude just computed. Computation of the amplitude at the next sample point subsequently is initiated, so that the analog voltage sup-

plied from the converter 16 comprises a musical wave-shape generated in real time.

The period of the computed waveshape, and hence the fundamental frequency of the generated note, is established by a frequency number R selected by the keyboard switches 12. A set of such frequency numbers corresponding to the notes of the instrument is stored in a frequency number memory 17. The wave shape itself, and hence the tonal quality of the produced musical note, is established by a set of harmonic coefficients C_n stored in a memory 18 and used in computing the Fourier components at each sample point.

The waveshape amplitude $X_0(qR)$ at each sample point is computed in accordance with the following discrete Fourier representation of a sampled periodic complex waveshape:

$$X_0(qR) = \sum_{n=1}^L C_n \sin \frac{\pi}{W} nqR \quad \text{for } q = 1, 2, 3, \dots \quad (9)$$

where R is the frequency number mentioned above, and $n = 1, 2, 3, \dots, L$ designates the Fourier component being evaluated. The value $n = 1$ corresponds to the fundamental, $n = 2$ to the second harmonic, $n = 3$ to the third harmonic, and so forth. The harmonic coefficient C_n specifies the relative amplitude of the respective n^{th} Fourier component.

The value W designates the maximum number of Fourier components included in any amplitude computation by the organ 10. In general, the use of 16 harmonics ($W = 16$) is quite satisfactory for synthesizing pipe organ sounds. The number L specifies the number of Fourier components included in a specific amplitude computation. In accordance with the present invention, the number L will depend on which note is being generated. Appropriate harmonic inhibit logic 20, illustrative embodiments of which are shown in FIGS. 2 and 5, limits the components only to those having frequencies below a preselected value preferably within the human hearing range. As discussed above, this reduces the computational rate requirements of the instrument 10.

The computer organ 10 of FIG. 1 implements equation 9 by computing the amplitude value $X_0(qR)$ for each sample point during a time interval t_x . The individual harmonic component amplitudes $F^{(n)} = C_n \sin(\pi/W) nqR$ for each of the L harmonic components are calculated separately during successive time intervals t_{cp} established by a clock 21 and a counter 22. At the first interval t_{cp1} the amplitude $F^{(1)}$ of the first harmonic ($n = 1$) is calculated. This value $F^{(1)}$ is placed in the accumulator 13. At the interval t_{cp2} the amplitude $F^{(2)}$ of the second Fourier component is computed and added to the accumulator 13 contents. At time t_{cp3} the third harmonic amplitude $F^{(3)}$ is calculated and added to the accumulator 16. The number W of iterations of this routine is controlled by the harmonic inhibit logic 20 in cooperation with the counter 22. The routine is terminated when all Fourier components associated with the particular amplitude computation have been evaluated. Upon such termination, the algebraic sum contained in the accumulator 13 will correspond to the amplitude

$$X_0(qR) = \sum_{n=1}^L F^{(n)} \quad (10)$$

for the sample point designated by the value qR .

As noted earlier, the waveshape amplitude $x_0(qR)$ in the accumulator 13 is gated to the digital-to-analog converter 16 at the end of the computation interval t_x . The accumulator 13 then is cleared by the signal on the line 15, and computation of the amplitude at the next sample point subsequently is initiated. The value qR is incremented and the L harmonic component amplitudes $F^{(n)}$ are calculated for the sample point designated by the new value of qR . Eventually the entire waveshape will be generated, the sound system 11 reproducing the musical note as the amplitude computations are carried out.

In the system of FIG. 1, a note interval adder 23 contains the value qR identifying the sample point at which the waveshape amplitude currently is being evaluated. This value qR is incremented at the beginning of each computation interval t_x by adding the selected frequency number R to the previous contents of the adder 23. The selected value R is supplied to the adder 23 via a gate 24 enabled by the t_x signal on the line 15. In general, the adder 23 is of modulo M where M is the product of the R number for any note times the number of points per period of that note. The value M is a system design constant related in part to the computational rate of the system.

To calculate each harmonic component, the values nqR (for $n = 1, 2, \dots, L$) are obtained in a harmonic interval adder 25 which is cleared before each amplitude computation cycle. Upon occurrence of the first t_{cp} clock pulse of a new cycle, the current value qR contained in the note interval adder 23 is entered into the harmonic interval adder 25 via a line 26 and a gate 27. At each subsequent clock pulse t_{cp} , the value qR is added to the previous contents of the adder 25. As a result, the harmonic interval adder 25 will contain the value nqR , where $n = 1, 2, \dots, L$ for the nth order harmonic component concurrently being evaluated. Preferably the harmonic interval adder 25 also is of modulo M.

An address decoder 28 accesses from a sinusoid table 29 the value $\sin(\pi/W) nqR$ corresponding to the argument nqR received via a line 30 from the harmonic interval adder 25. The sinusoid table 29 may comprise a read only memory storing values of $\sin(\pi/W) \phi$ for $0 \leq \phi \leq 2W$ at intervals of D, where D is called the resolution constant of the memory.

The value $\sin(\pi/W) nqR$, supplied via a line 31, is multiplied by the coefficient C_n for the corresponding n^{th} harmonic by a multiplier 32. The multiplication product represents the amplitude $F^{(n)}$ of the nth harmonic component and is supplied via the line 33 to the accumulator 13. The appropriate coefficient C_n is accessed from the harmonic coefficient memory 18 by an address control unit 34 advanced by timing signals received from the counter 22 via a line 35. Readout from the harmonic coefficient memory 18 is inhibited by the harmonic inhibit logic 20 for those higher order Fourier components not included in a particular amplitude computation. This is facilitated via an enable/inhibit signal line 36.

FIG. 2 shows illustrative circuitry 20A useful as the harmonic inhibit logic 20 of FIG. 1. With this circuitry, each waveshape amplitude computation is performed in a fixed time interval t_x , regardless of how many Fou-

rier components are included in that computation. The interval t_x is established by the counter 22 which receives t_{cp} pulses at the system clock rate f_c from the clock 21 via a line 37. The counter 22 preferably is of modulo 16, and produces on the lines 35a - 35d a four-bit binary signal designating the respective calculation timing pulses t_{cp1} through t_{cp16} . As indicated by the timing diagram of FIG. 4, these timing signals occur sequentially within the time interval t_x . The t_x signal is obtained as the counter 22 resets.

When a note between G $\#_5$ and C₇ is selected at the keyboard switches 12, an input will be provided to the logic 20A on the correspondingly designated line. Encoding circuitry 40 including the OR gates 41 - 46 and a one-of-ten to binary encoder 47 provide on the lines 48a - 48d a signal specifying in binary code the highest Fourier component (L) to be included in the wave-shape amplitude computation for that note.

At the beginning of each computation cycle, a flip-flop 49 is set to "1" by the t_x signal on the line 15. The "1" output of the flip-flop 49 functions as an enable signal on the line 36 to the harmonic coefficient memory 18. Thus during the initial computation cycles t_{cp1} , t_{cp2} , ..., the flip-flop 49 remains set to "1", the memory 18 is enabled, and calculation of the Fourier coefficients is not inhibited.

The computation pulses t_{cp1} , t_{cp2} , ... from the counter 22 are compared with the maximum harmonic designation signal (L) on the lines 48a - 48d by a comparator 50. When coincidence occurs, indicating that the highest harmonic concurrently is being evaluated and that subsequent harmonics must be inhibited, an output signal is produced on the line 51 from the comparator 50. After a brief delay (less than an interval t_{cp}) provided by a delay circuit 52, the coincidence output signal from the comparator 50 resets the flip-flop 49 to "0". This terminates the enable signal on the line 36 and inhibits subsequent readout from the harmonic coefficient memory 18. As a result, on subsequent calculation times when higher harmonics normally would be evaluated, the output of the harmonic coefficient memory 18 is zero. The output $F^{(n)}$ of the harmonic amplitude multiplier 32 likewise is zero. The higher harmonics effectively are inhibited.

The encoding circuitry 40 of course is selected with reference to the highest harmonic (L) desired for each note being produced. Thus for the illustrative example of Table I, the signals provided on the lines 48a - 48d will correspond to the binary representation of the value L listed in that table. For example, when the key G $\#_5$ is selected, an input to the one-of-ten to binary encoder 47 occurs on the line 54. The encoder 45 produces on the lines 48a - 48d a signal L = 15. When the counter 22 reaches the time interval t_{cp15} , the signal on the lines 35a - 35d will be identical to that on the lines 45a - 48d. As a result, the comparator 50 will produce a coincidence output, thereby resetting the flip-flop 49 and inhibiting readout from the harmonic coefficient memory during the time t_{cp16} (see FIG. 4). The sixteenth Fourier coefficient thus is not included in the amplitude computation.

Similarly, when the note A $\#_6$, B₆ or C₇ is selected, the OR gate 46 provides an output on a line 55, causing the encoder 47 to provide on the lines 48a - 48d the binary representation of the value L = 6. The comparator 50 then will cause the flip-flop 49 to be reset to "0"

after t_{cp6} , thereby effectively inhibiting calculation of the seventh through 16th Fourier components.

When any note between C₁ and G₅ is selected, the encoder circuitry 40 receives no input. Accordingly, the signal (binary 0000) on the lines 48a - 48d will represent L = 16. The flip-flop 49 will remain set at "1" throughout the entire computation cycle and all sixteen harmonics will be calculated.

The harmonic coefficient memory 18 and the memory address control 34 advantageously are implemented using a commercially available integrated circuit read-only-memory (ROM) such as the Signetics type 8223. This device includes address control circuitry which accepts a binary coded address like that provided on the lines 35, and automatically accesses from the corresponding memory storage location a word of up to eight bits. The same integrated circuit includes memory output enable/inhibit circuitry controlled by a "chip enable" input to which the line 36 (FIG. 2) may be connected. The actual harmonic coefficient values stored in the memory 18 are of course a design choice which will depend on the desired tonal quality of the sound being produced by the organ 10. By way of example only, the following Table II lists typical harmonic coefficient values C_n which will produce a diapason-type organ sound.

TABLE II (DIAPASON)

Coefficient	Value stored in memory 18	
	(Relative Amplitude)	(Decibel Equivalent)
C ₁	127	0 db
C ₂	71	-5
C ₃	90	-3
C ₄	36	-11
C ₅	23	-15
C ₆	25	-14
C ₇	8	-24
C ₈	8	-24
C ₉	4	-31
C ₁₀	4	-31
C ₁₁	2	-38
C ₁₂	2	-38
C ₁₃	2	-38
C ₁₄	1	-42
C ₁₅	1	-42
C ₁₆	1	-42

The one-of-ten to binary encoder 47 may comprise a conventional diode array having ten input lines and four, binary coded output lines. Such devices are shown in the standard text entitled "Computer Logic" by Ivan Flores, Prentice Hall, 1960 at Chapter 11.8. The counter 22 may be implemented using a Signetics type 8280 four-bit binary counter contained in a single integrated circuit chip. The comparator 50 may comprise a Signetics type 8269 integrated circuit four-bit comparator.

In an alternative version of the logic 20A, the encoding circuitry 40 may be eliminated. The number L specifying the highest Fourier component to be computed for each note then may be stored in the memory 17 along with the corresponding frequency number R. When a note is selected at the switches 12, the associated L number will be accessed from the memory 17 and supplied via the lines 54a-54d directly to the comparator 50. The logic 20A will function as just described to limit harmonic production.

Using the harmonic inhibit logic 20A of FIG. 2, the computer organ 10 of FIG. 1 will compute each sample point amplitude in a fixed time interval t_x regardless of how many Fourier components are included in that computation. This is reflected by the waveforms of

FIG. 3, which indicate typical amplitude values supplied to the digital-to-analog converter 16 during production of the notes C₇, F₆ and G₅. Although successive sample point amplitudes are computed at fixed time intervals t_x , the number of points computed per period will differ for each note.

The system clock rate f_c may have the minimum value given above in equation 7 (or in Eq. 8 for a polyphonic system). In practice however, the clock rate will be selected slightly higher than the minimum value, to provide a safety factor S greater than 1.000 for the Nyquist criteria. To minimize the likelihood of producing undesirable beat notes or noise, this safety factor may be chosen to be slightly greater than $2^{1/12}$ which is the interval between two adjacent tones in an equally tempered scale. For example, the safety factor may be selected as $S = 2^{1.37/12} = 1.082$. Using this safety factor, the Nyquist frequency f_N^* and the clock rate f_c^* for a monophonic instrument system will be:

$$f_N^* = Sf_N = (1.082) (2) (12.841 \text{ kHz}) = 27.797 \text{ kHz} \quad (11)$$

$$f_c^* = Sf_c = 16 Sf_N^* = (1.082) (410.9 \text{ kHz}) = 444.59 \text{ kHz} \quad (12)$$

The clock 21 utilized with the logic 20A of FIG. 2 thus may have this frequency f_c^* . For such an embodiment, the waveshape amplitudes will be computed at successive fixed time intervals $t_x = 1/f_N^*$ so that the number of sample points per period of the generated note will be given by:

$$\begin{aligned} \text{points/period} &= (\text{period of note/computation interval}) \\ &= f_N^*/f(\text{note}) \end{aligned} \quad (13)$$

For example, for note C₇ ($f_{C7} = 2.093 \text{ kHz}$) there will be $f_N^*/f_{C7} = (27.797 \text{ kHz})/(2.093 \text{ kHz}) = 13.3$ points computed per period of the generated waveshape. Table III below includes a list of the points per period for other notes between C₅ and C₇. The frequency numbers R utilized with such a monophonic, single channel embodiment also are set forth in Table III. These values are obtained from the following relationship:

$$R = [W f(\text{note})]/f_N^* \quad (14)$$

For example, for C₇ the frequency number is:

$$R_{(C7)} = [(16)(2.093 \text{ kHz})]/[27.797 \text{ kHz}] = 1.20474 \quad (\text{Eq. 15})$$

In general, the frequency numbers R are non-integers. Thus the note interval adder 23 (FIG. 1) will not "reset" exactly to zero at the end of each period of the generated waveshape, but rather to a number which differs each period. Thus consecutive periods of the same note will have sample point amplitudes slightly different than those of the preceding period. This effect is beneficial in a polyphonic system since it provides "decoupling" when two notes are played simultaneously.

TABLE III

Note	Frequency	R Number	Points/Period
C ₇	2093.00	1.20474	13.3

Fig. 5 shows an alternative embodiment 20B for the harmonic inhibit logic 20 of FIG. 1. In this embodiment, the counter 22b provides a separate output on one of the sixteen lines designated t_{cp1} through t_{cp16} for each of the corresponding calculation times. The harmonic coefficient memory 18b is implemented by a set of sixteen registers 61a - 61p which store the respective harmonic coefficients C₁ through C₁₆. The memory address control 34b readily is implemented by a set of gates 62a - 62p each associated with the corresponding register 61a - 61p and operated by the respective signals t_{cp1} - t_{cp16} received from the counter 22. Thus when the first calculation timing signal t_{cp1} occurs, the gate 62a gates the coefficient C₁ from the register 61a via a bus 63 to the harmonic amplitude multiplier 32.

The harmonic inhibit logic 20B functions to reset the counter 22a after the highest desired Fourier component has been calculated. For example, if the key C₇ is selected at the keyboard switches 12, the signal on the C₇ line is supplied via an OR gate 64 to enable an AND gate 65. When the timing pulse t_{cp6} occurs, resulting in calculation of the sixth harmonic, the pulse t_{cp6} is gated via the AND gate 65 to a bus 66. After a delay of less than the time interval t_{cp} , provided by a delay circuit 67, the computation time interval pulse t_x' is generated. This resets the counter 22b and terminates the current waveshape amplitude computation. The seventh and higher Fourier components are not evaluated, and computation of the waveshape amplitude at the next sample point begins immediately. Eventually the waveshape C₇ shown in FIG. 6 will be generated.

When using the circuitry 20B of FIG. 5, the duration t_x' taken to compute each amplitude sample point will not be a constant for all notes, but will depend on the number of Fourier components computed for each note. Thus, for example, when the note D $\#_6$ is selected, the signal provided via an OR gate 68 will enable an AND gate 69. During calculation of the tenth harmonic, the signal t_{cp10} will be gated via the AND gate 69 onto the bus 66. This will cause termination of the amplitude computation cycle after evaluation of the first ten Fourier components, and immediately initiate computation of the next sample point amplitude. As a result, the generated D $\#_6$ waveform will have the appearance shown in FIG. 6. Note that for D $\#_6$ each sample point interval has a duration $t_x' = 10t_{cp}$, whereas for the C₇ waveshape, the duration $t_x' = 6t_{cp}$. The various OR gates 70 - 74 and AND gates 75 - 81 cooperate to gate onto the bus 66 the timing sig-

nal $t_{cp7} - t_{cp15}$ appropriate for limiting harmonic generation for the selected note.

For notes between C_1 and G_5 , all 16 harmonics are generated. In this instance, the t_{cp16} signal on the line 82 is supplied directly to the buss 66 to reset the counter 22b and terminate the computation cycle at the end of sixteen t_{cp} intervals. As a result, (FIG. 6) the notes G_5 and D_5 and all others of lower fundamental frequency are generated with sample point intervals of equal length $t_x' = 16t_{cp}$. Of course, each of these notes G_5 through C_1 will have a different number of sample points per period.

Although only monophonic embodiments are illustrated in FIGS. 1 - 6, the invention is not so limited. Harmonic limiting thus can advantageously be employed in a polyphonic system, such as that described in the above identified patent application entitled COMPUTER ORGAN. In such a polyphonic system, the waveshape amplitude supplied to the digital-to-analog converter is the sum of the separately computed amplitudes for each note of the chord being played. Such computation may be accomplished on a time sharing basis, as illustrated diagrammatically in FIG. 7 for a ($K = 3$) polyphonic system in which three notes may be played simultaneously.

Referring to FIG. 7 each fixed computation interval t_x includes three consecutive subintervals t_A , t_B , t_C during which the amplitudes for three notes are computed separately. Each of these subintervals includes 16 shorter intervals t_{cp}' during which the individual Fourier components associated with the respective notes are calculated. For example, if the chord C_6 , E_6 , G_6 is played, the C_6 amplitude may be computed during the interval t_A , and the E_6 and G_6 amplitudes computed during the t_B and t_C intervals respectively.

Harmonic limiting of the type described herein then may be utilized independently during each subinterval t_A , t_B , t_C to inhibit calculation of harmonics above the respective L value for the selected notes. Thus for the chord C_6 , E_6 , G_6 , the harmonic limiting circuitry will inhibit Fourier component calculation after evaluation of the $L = 12$, $L = 9$ and $L = 8$ components respectively during the intervals t_A , t_B and t_C , as indicated in FIG. 7.

FIG. 8 shows how harmonic limiting may be applied to a COMPUTER ORGAN USING PARALLEL PROCESSING such as that shown in the above mentioned patent application Ser. No. 298,365. In the illustrated system 90, the odd-valued Fourier components ($n = 1, 3, 5, \dots$) are calculated in a first processing channel 91, and the even harmonics ($n = 2, 4, 6, \dots$) concurrently are calculated in a parallel processing channel 92. The individual components evaluated in the channels 91 and 92 are summed in an adder circuit 93 and supplied via a line 33' to an accumulator 13, digital-to-analog converter 16 and sound system 11 like that of FIG. 1. Note selection is accomplished by keyboard or pedal switches 12 cooperating with a frequency number memory 17' which supplies the selected R numbers via a line 94 to both processing channels 91, 92.

The memory 17' may contain the L number itself, or some other coded designation associated with this L number. When a note is selected at the keyboard switches 12, the designation code is supplied via a line 95 to a harmonic limit memory 96 advantageously implemented by a Signetics type 8223 integrated circuit read-only-memory or like device. The designation code

causes the access control circuitry 96a to read out from the memory 96 the stored contents specifying the highest order odd (L_{odd}) and highest order even (L_{even}) Fourier component to be calculated. These values are supplied via the respective lines 97, 98 to appropriate comparators 99, 100 associated with the respective processing channels 91, 92. The comparator 99 compares the value L_{odd} with a signal supplied via a line 101 indicating which component presently is being calculated in the channel 91. When coincidence is obtained, the comparator 99 causes an inhibit circuit 102 to prevent calculation by the channel 91 of all higher order odd Fourier components. The comparator 100 and the inhibit circuit 103 function in like manner for the channel 92.

By way of example, an arbitrary designation code "0001" may be stored in the memory 17' together with the R numbers associated with the notes C_7 , B_6 and A_6 . When one of these notes is played, the code "0001" will be supplied to the memory access control 96a, causing readout from a certain storage location in the memory 96. This location advantageously contains the values $L_{odd} = 5$ and $L_{even} = 6$. Accordingly, calculations in the channels 91 and 92 will be inhibited respectively after evaluation of the 5th and 6th Fourier components, exactly as required for the illustrative L values of Table I. Intending to claim all novel, useful and unobvious features shown or described, the inventor makes the following claims.

I claim:

1. In a musical instrument of the type wherein the amplitudes of a waveshape are computed for successive waveshape sample points at certain regular time intervals from stored harmonic coefficient values, each amplitude being computed by individually calculating a set of constituent Fourier components of said waveshape, each Fourier component being calculated by multiplying a trigonometric function of the waveshape sample point by a harmonic coefficient value which establishes the relative amplitude of that Fourier component, said instrument providing a signal indicating which order Fourier component currently is being calculated, said calculated components being combined to obtain the waveshape amplitude at each sample point, musical notes being produced by converting said computed waveshape amplitudes for successive sample points to musical sounds as said computations are carried out, the improvement wherein said instrument includes note selection switches and harmonic inhibit logic for limiting the components in said set only to those having a frequency below a certain value within the normal human hearing range, said harmonic inhibit logic comprising:

55 circuitry providing, in response to switch selection of each note, a signal designating the highest order Fourier component to be calculated for that note,

60 a comparator for comparing said highest-order-designating signal and said order-indicating signal, and for providing an output when the compared signals are equal,

65 inhibit circuitry for inhibiting calculation of higher order Fourier components in response to occurrence of said comparator output.

2. A musical instrument according to claim 1 wherein said certain value is approximately 13 kHz, wherein said set normally includes the first sixteen Fourier com-

ponents for each note between C_1 and G_5 , and wherein said set includes less than 16 Fourier components for each note between $G_{\#5}$ and C_7 .

3. A musical instrument according to claim 1 comprising:

a clock providing timing pulses t_{cp} establishing the Fourier component calculation rate of said instrument,
a counter receiving said timing pulses t_{cp} and establishing each amplitude computation regular time interval t_x , the count of said counter during each computation interval establishing which order Fourier component currently can be calculated by said instrument, said order-indicating signals being indicative of said count.

4. A musical instrument according to claim 3 wherein said amplitudes are computed digitally and are converted by a digital-to-analog converter, wherein said computation interval t_x is of fixed duration regardless of which note is being produced, wherein said digital-to-analog conversion occurs at the end of each interval t_x , and wherein for notes having inhibited Fourier components, the uninhibited components are calculated in a time interval less than t_x .

5. In an electronic musical instrument of the type wherein the amplitudes at successive sample points of a musical waveshape are computed by individually calculating the waveshape discrete Fourier components and combining said components to obtain each amplitude, said amplitudes being converted to musical notes as said computations are carried out, the Fourier components included in each amplitude computation being limited only to those having frequencies below a certain value, said instrument comprising:

a memory storing frequency numbers associated with each note and establishing the separation between successive amplitude sample points,

note selection means for accessing from said memory the frequency number associated with a selected note,

means for providing, in response to selection of a note, a signal designating the highest order L harmonic to be calculated for that note,

Fourier component evaluation circuitry, utilizing said associated frequency number, for calculating as many as W Fourier components for each amplitude computation, all W of said components being calculated and combined to obtain said amplitudes during production of each note for which the Wth component has a frequency below said certain value, said evaluation circuitry providing a signal indicating which Fourier component n currently is being calculated,

a comparator for detecting coincidence between the values n and L , and

harmonic inhibit logic, operative upon detection by said comparator of coincidence between the values n and L , for inhibiting calculation by said evaluation circuitry of Fourier components of order higher than L .

6. A musical instrument according to claim 5 wherein said certain value is within the normal human hearing range.

7. A musical instrument according to claim 5 wherein said memory also stores a highest order harmonic designation code for each note, said harmonic inhibit logic being responsive to the designation code accessed from

said memory together with said associated frequency number when a note is selected.

8. A musical instrument according to claim 7 wherein said code itself comprises said signal designating the value L .

9. A musical instrument according to claim 7 further comprising a harmonic limit memory containing certain L designating values, said code causing access from said harmonic limit memory of the L designating value associated with the selected note.

10. A musical instrument according to claim 5, said instrument being polyphonic and comprising:

like means for separately computing a note-related amplitude for each note played simultaneously, said note-related amplitudes being summed to obtain each waveshape amplitude, and harmonic inhibit logic operable separately to limit the Fourier components included in the computation of each note-related amplitude.

11. A musical instrument according to claim 5 wherein different subsets of said Fourier components are calculated concurrently in separate parallel processing channels, said harmonic inhibit logic being operable separately to limit the Fourier components computed by each processing channel.

12. A musical instrument according to claim 5 including a clock for controlling the rate at which individual Fourier components are calculated by said evaluation circuitry, said rate being established by the single highest frequency f_h of any uninhibited component included in the amplitude computation for any note, said rate being a multiple of the Nyquist frequency $2f_h$ times a safety factor S having a value greater than 1.000.

13. A musical instrument according to claim 12 wherein for a polyphonic instrument capable of simultaneously producing K notes, said multiple is K , and wherein for an instrument having P parallel processing channels, said multiple is $1/P$.

14. A musical instrument according to claim 5 wherein each amplitude is computed within a fixed time interval t_x , and further comprising a clock establishing identifiable calculation intervals within said interval t_x during which certain of said components may be calculated by said evaluation circuitry, said harmonic inhibit logic being responsive to said identifiable calculation intervals and to said value L for inhibiting calculation of Fourier components of order higher than L .

15. In an electronic musical instrument of the type having:

first means for computing during consecutive time intervals the amplitudes $X_0(qR)$ of a waveshape, where q is an integer incremented each time interval, in accordance with the relationship

$$X_0(qR) = \sum_{n=1}^L C_n \sin \frac{\pi}{W} nqR \quad \text{for } n=1, 2, 3, \dots, L$$

wherein L signifies the number of Fourier components included in each amplitude computation for a particular note, W is the maximum number of components included in the computation for any note produced by said instrument, C_n is the coefficient of the corresponding n^{th} Fourier component, and R is a number specifying

ing the period of said waveshape, said first means comprising:

- a harmonic coefficient memory storing said harmonic coefficients C_n ,
- a memory containing a table of sinusoid values,
- a frequency number memory containing values R for a selectable set of notes,
- a keyboard including note selection switches, actuation of any keyboard switch causing access from said frequency number memory of the R value corresponding to the note selected by that actuated key,
- harmonic component evaluation circuitry utilizing said harmonic coefficient memory and said table to calculate $F^{(n)} F^{(n)} = C_n \sin \pi/W nqR$ for each Fourier component in accordance with the accessed value R, and
- an accumulator for algebraically summing the calculated values $F^{(n)}$, and

second means responsive to said first means for producing musical notes for said computed amplitudes,

the improvement wherein for each produced note the value L is such that all of the Fourier components included in the amplitude computation have frequencies below some preselected frequency within the human hearing range, said improvement comprising:

harmonic inhibit logic responsive to actuation of at least some keyboard switches for inhibiting said harmonic component evaluation circuitry from calculating $F^{(n)}$ for those Fourier components of the note selected by said actuated switch which are higher in frequency than said preselected frequency.

16. A musical instrument according to claim 15 wherein said frequency number memory stores values of R together with codes designating the value of L associated with each R value, and wherein actuation of each key causes access from said frequency number memory of the corresponding value R and of the L-designating code associated therewith, and

wherein said harmonic inhibit logic is responsive to

the accessed L-designating code and inhibits access from said harmonic coefficient memory of the coefficients associated with Fourier components of order higher than L, thereby effectively preventing calculation by said evaluation circuitry of harmonics having frequencies above said preselected frequency.

17. A musical instrument according to claim 16 wherein said harmonic component evaluation circuitry calculates all W Fourier components for each note unless inhibited, wherein said harmonic inhibit logic comprises circuitry for detecting coincidence between the value L designated by said code and a signal indicating which Fourier component currently is being calculated by said evaluation circuitry, said harmonic inhibit logic inhibiting readout from said harmonic coefficient memory for the remainder of each amplitude computation interval after detection of such coincidence.

18. A musical instrument according to claim 17 wherein each waveshape amplitude is computed in a fixed time interval t_x regardless of which note is being produced, said instrument including a clock and a counter cooperating therewith to establish said intervals t_x , and wherein said Fourier component indicating signal is derived from the timing output of said clock and counter.

19. A musical instrument according to claim 15 wherein said evaluation circuitry provides a signal indicating which order Fourier component currently is being evaluated, said harmonic inhibit logic including;

circuitry, responsive to actuation of said certain keyboard switches, for providing a signal specifying the value L for the note selected by the actuated key,

a comparator for comparing said L-specifying signal and said order-indicating signal, said comparator providing an output when the compared signals are the same, and

means, responsive to said comparator output, for inhibiting calculation of higher order Fourier components for the selected note.
